Corporation, a corporation of Indiana**

Application January 24, 1944, Serial No. 519,430

16 Claims. (Cl. 274—10)

1

This invention relates generally to automatic phonograph apparatus and more particularly to drop-down record changing apparatus having novel means for supporting a stack of records and novel means for separating and releasing records to the turntable.

One form of conventional record changing apparatus for automatically dropping records to a turntable includes a plurality of peripheral supports for engaging the outer edge of the lowermost record in the stack together with a means associated with one of said supports for shifting the lowermost record in a lateral direction to release it to the turntable. Another conventional form of drop-down record changing apparatus includes for supporting a plurality of records the combination of a support associated with the centering spindle and a single peripheral support cooperating therewith whereby records may be shifted laterally and released to the turntable. A third type of well-known drop-down record changing apparatus includes a centering spindle which comprises the sole support of the entire stack of records. In all of these forms of record changing apparatus, it is conventional practice to successively and automatically drop one record at a time to the turntable by sliding the lowermost record out of engagement with the supporting structure. In so doing, it is characteristic that the entire stack of records drops as a unit and impacts the supporting means either at certain points on the periphery of the lowermost record or at a point adjacent the centering aperture of the lowermost record. When there are several records remaining in the stack, and particularly in the case of several large records remaining in the stack, there is heavy impact on a very small area of the lowermost record either on the periphery or adjacent the centering aperture which usually cracks or otherwise mutilates that record. Similar injury can result when a stack of records is carelessly placed on the supporting structure. Obviously such injuries to records decrease their useful life and result in the loss of many otherwise undamaged records.

Accordingly, the principal object of this invention is to provide a novel record changing apparatus characterized by its ability to so handle records that damage to the records may be reduced to a minimum.

A further object of this invention is to provide in a record changing apparatus a novel record supporting and handling structure for removing from the lowermost record the weight of superimposed records whereby during a record changing

2

cycle to prevent impact between the superimposed records and the supporting structure.

A still further object of this invention is to provide in a record changing apparatus auxiliary record supporting structure characterized by its ability to support all but the lowermost record during the period that said record is moved from the stack to the turntable.

In accordance with the present invention, there is provided an automatic record changing apparatus comprising a turntable, a pickup arm pivotally mounted adjacent the turntable, a change-cycle control mechanism and a first peripheral supporting means for engaging the peripheral edge of the lowermost record in the stack of records. The supporting means includes a means for sliding the lowermost record laterally with respect to the stack and is adjustable for supporting either a stack of small records or a stack of large records. There is also provided a centering spindle including a shoulder for engaging the edge of the centering aperture of the lowermost record in the stack and cooperating with the peripheral support to support the stack of records over the turntable in a position to be successively and automatically dropped thereon. Incorporated in the change-cycle control mechanism is a cam for moving the spindle in a vertical direction during the record changing cycle to elevate the stack of records above its normal plane. For supporting the records in this position, there is provided a pair of auxiliary supports which are rotatably mounted adjacent the periphery of the turntable and are movable into a position to engage the periphery of the stack of records when it is in its elevated position. While the records are supported on the first peripheral support and the auxiliary peripheral supports, the spindle is lowered out of engagement with the lowermost record in the stack and that record is moved laterally until its centering aperture is in a position to clear the shoulder on the centering spindle. Thereafter the spindle is elevated into engagement with the record immediately above the lowermost record to lift the stack free of the lowermost record. At this time, the change-cycle control mechanism separates the first peripheral support and the auxiliary supports to drop the lowermost record to the turntable. As in conventional record changers, the tone arm is then moved into engagement with the record.

For a better understanding of the invention, together with other and further objects thereof, reference is made to the following description, taken in connection with the accompanying draw-

ings, and its scope will be pointed out in the appended claims.

In the accompanying drawings:

Fig. 1 is a top plan view of the record changing apparatus constructed in accordance with the invention.

Fig. 2 is a side-elevation view, partly in section and broken away in parts, of the apparatus shown in Fig. 1 and taken from the right-hand side thereof.

Fig. 3 is a rear-elevation view of the apparatus shown in Fig. 1 and includes a section taken on line 3—3 of Fig. 2.

Fig. 4 is a bottom view of Fig. 1.

Fig. 5 is a side-elevation view, with parts broken away, of the record-moving apparatus which is shown in section in Fig. 3.

Fig. 6 is a perspective taken from underneath the record-changing apparatus illustrated in Fig. 1.

Fig. 7 is a perspective taken from above the change-cycle control mechanism illustrated in Fig. 6.

Fig. 8 is a sectional view taken on line 8—8 of Fig. 1.

Fig. 9 is a partial top plan view of a modification of the record changer apparatus illustrated in Fig. 1.

Fig. 10 is a side-elevation view of the modified apparatus illustrated in Fig. 9.

Fig. 11 is a bottom plan view of the modified apparatus illustrated in Figs. 9 and 10.

Referring to the drawings, the invention therein illustrated embodies phonograph apparatus comprising a base plate 10 having a bracket 11 fixed thereto for supporting a rotatable hollow shaft 12 to which is fixed turntable 14. There is also provided a tone arm 16 pivoted for vertical and horizontal movement on a pedestal 27 fixedly mounted on base plate 10. There is provided on the tone arm a pickup 17 for reproducing records on the turntable.

For driving shaft 12 and turntable 14, there is provided a pulley 18, connected to motor 19, and engaging friction wheel 20, which in turn engages the inner surface of the flange on turntable 14.

For supporting a stack of records above the turntable in a position to be dropped thereto, there is provided, within hollow shaft 12, a spindle 22. Cooperating with the spindle is a peripheral support including a rotatable bracket 30 suitably mounted on a pedestal 31. Bracket 30 includes oppositely disposed shelves 32 and 33 for supporting either large or small records. Slideable member 35 rests on a rotatable extension 36 of pedestal 31 and is provided with auxiliary record supporting shelves 38 and 39 disposed in a plane substantially common with the plane of shelf 24 on spindle 22 and spaced from the turntable for supporting the lowermost record of a stack of 10-inch or 12-inch records. Extension 36 includes a rotatable shaft 41, which extends downwardly within pedestal 31. Flange portion 42 of shaft 41 engages shoulder 43 of pedestal 31 which forms a rotatable support for shaft 41. Flange portion 42 includes a pair of bosses 45 for engaging notches 46 in shoulder 43. Bosses 45 and notches 46, respectively, are spaced 180° apart whereby to provide two positions for bracket 30 so that either shelf 32 or shelf 33 may be accurately positioned for supporting a stack of small or large records. Spring member 48 anchored to pedestal 31 and engaging the upper surface of flange 42 urges the bosses

45 into the notches 46 to retain the bracket in either of the two positions mentioned above.

For positioning the pickup arm 16 over the initial playing groove of either a small record or a large record, lower end 44 of shaft 41 is beveled. Pin 50 extends downwardly from the lower end of shaft 41 and is biased by spring 51 into engagement with the beveled portion 44 of shaft 41. When the bracket 30 is rotated 180° from the position shown in Fig. 1 to a position for supporting large records, beveled portion 44 of shaft 41 moves pin 50 downwardly into such a position that it functions to position the pickup arm over the initial playing groove of the large record as will be described hereinafter. As will be obvious from inspection of the drawings, spring 51 returns pin 50 to the position shown in Fig. 3 when the bracket 30 is rotated to a position for supporting small records whereby pickup arm 16 is also controlled to move into alignment with the initial playing groove of such records.

For moving record moving member 35, there is provided a lever 54 pivoted on pin 55 which is suitably fixed to pedestal 31. Lever 54 extends upwardly through shaft 41 into an aperture 56 provided in member 35. The lower portion of lever 54 extends downwardly through aperture 58 in base plate 10 into engagement with lever 60 pivotally mounted for movement in a horizontal plane on stud 61. Member 35 is normally biased to the position shown in Fig. 2 by spring 62 anchored to lever 54 at its lower end and to base plate 10.

For centering the records above the turntable and guiding them to the turntable, there is provided a movable spindle 22 extending upwardly through turntable shaft 12. Spindle 22 is provided with a notched portion 23 which forms a record supporting shoulder 24 for cooperating with bracket 30 to support the stack of records. Above the shoulder 24 and pivoted within a slot in spindle 22, there is provided member 25, having slot 26, for guiding the records by engaging all except the lowermost record. Thus when there are several records in the stack, member 25 guides them toward bracket 30 and into position to engage shoulder 24 and shelves 32 or 33. Without member 25, the records would be permitted to remain aligned with the lower portion of spindle 22, in which position they would drop to the turntable. When records are removed from turntable 14, slotted member 25 is engaged by the records and moved upwardly and into alignment with the body of spindle 22.

For elevating spindle 22 and the stack of records during a record changing cycle, there is provided a spring biased lever 70, one end of which engages the lower end of spindle 22 and the other end of which engages cam 71. Lever 70 is pivoted on ear 72 formed integrally with plate 73 which is fixed between bracket 11 and studs 74 and 75 which are fixed from base plate 10. For biasing lever 70, there is provided a spring 76 which is fixed between lever 70 and plate 73. Thus when there are no records on spindle 22, the spring 76 pivots the lever in a clockwise direction whereupon the spindle is raised to the dotted-line position shown in Fig. 2.

For engaging the lowermost record in the stack during the record changing cycle, there is provided a pair of horizontally movable auxiliary record supporting members 80 which are disposed with respect to bracket 30 as best indicated in Fig. 1. Members 80 are arranged to be rotatable within pedestals 81 whereby the upper ends of

members 80 may be rotated into engagement with the lowermost record of the stack. For rotating members 80, there is provided on the lower ends of each of them the crank members 82 connected to be moved in unison by tie-rod 83. Lever 85 is fixed to one of the members 82 as illustrated in Fig. 4 and pivoted on a stud 86 whereby to simultaneously rotate members 80 into engagement with the lowermost record of the stack. The end 87 of lever 85 is biased into contact with cam 89 by a spring 90 which is anchored to one of the members 82 and to the base plate whereby lever 85 and members 82 follow the motion imparted thereto by cam 89.

As stated hereinbefore, tone arm 16 is supported for vertical and horizontal movement on pedestal 27. For moving tone arm 16 in a horizontal plane, there is provided within pedestal 27 a hollow shaft 91, to which is clamped a crank arm 92 having a lug 93 at the end thereof projecting downwardly into engagement with an L-shaped lever 95. Lever 95 is pivoted at one end thereof to base plate 10 at 96, the other end 97 of this lever being disposed to engage cam 100 whereby the lever is oscillated in a horizontal plane during the record changing cycle. Lug 93 projects through aperture 98 in lever 95 which is elongated to allow tone arm 16 free movement over the playing grooves of the record. For biasing the tone arm toward the center of the turntable, there is provided a spring 99 which is fixed between lug 93 and base plate 10 to be lightly tensioned as the tone arm approaches the limit of its outer movement.

Lever 95 is provided with an extension 102 for engaging with pin 50 associated with record supporting bracket 30. As explained hereinbefore, when bracket 30 is rotated into position for supporting small records, pin 50 is in its uppermost position but when bracket 30 is rotated to support large records, surface 44 of shaft 41 cams pin 50 downwardly into the path of extension 102 on lever 95. Referring to Fig. 4, when lever 95 moves in a clockwise direction to return tone arm 16 into position to engage the initial playing groove of a record, pin 50, when moved downwardly, engages extension 102 to stop the movement of lever 95 and also tone arm 16 in alignment with the initial playing groove of a large record.

For elevating tone arm 16 during a record changing cycle, there is provided a vertically movable pin 103 within hollow shaft 91 for engaging the under side of tone arm 16. Spring 104 abuts hollow shaft 91 and a collar on pin 103 to exert downward pressure for retaining pin 103 in its lowermost position. For controlling the movement of pin 103, there is provided a lever 105, one end of which engages with the pin and the other end of which engages cam 107 on cam gear 140. Lever 105 is pivoted to a turned-up ear 106 provided on the supporting plate 73 whereby downward motion of the end 108 of lever 105 elevates pin 103.

For controlling the inward swing of tone arm 16 after all records have been placed on the turntable and after the last record is played, there is provided a lever 112 also pinned to the ear 106 on plate 73. Lever 112 is so disposed that one end thereof is movable adjacent the edge of cam 107. The other end in the form of a hook 113 projects upwardly to engage with an extension 115 of lever 95. Thus lever 112 can be moved to place the portion 113 in the path of projection 115 to limit the movement of lever 95 and the movement

of crank arm 92 whereby to limit the inward movement of tone arm 16. Lever 112 is so operated by a rotatable plate 117 comprising a downwardly-extending lug 118 which is movable about the pivot 119 into the path of the end 120 of lever 112. Spring 114 secured to plate 73 and ear 116 biases end 120 into the path of lug 118.

There is also provided on plate 117 a lug 121 for engaging an arm 124 connected with switch 130, the operation of which will be described hereinafter. Plate 117 is rotatable by the upper portion 77 of lever 70. When lever 70 is in the full-line position shown in Fig. 2, portion 77 engages lug 121 to rotate lever 117 in a counterclockwise direction whereby lug 121 is moved into position to engage arm 124 of switch 130. When plate 117 is in this position, lug 118 is displaced so that it does not engage lever 112 and thus arm 113 of lever 112 intercepts arm 115 of lever 95 to prevent the tone arm from swinging inwardly over the last record on the turntable. When lug 121 engages arm 124, switch 130 is rotated to the off-position.

For operating the trip mechanism hereinafter to be described, there is provided a lever 132 pivoted on hollow shaft 91 which is associated with tone arm 16. On lever 132 there is provided a turned down ear 133, the purpose of which will subsequently be explained. Lever 132 is moved when tone arm 16 rotates by reason of the engagement therewith of a clutch member 134. This consists of a collar 135 fixed to shaft 91 and in engagement with the upper surface of lever 132. Frictional member 136 engages the lower surface of lever 132 and the clamp portion of lever 92 also fixed to shaft 91. Through the frictional engagement between lever 132 and shaft 91, the lever is caused to rotate with tone arm 16 as the stylus tracks the playing grooves of the record.

For controlling a record-changing cycle, there is provided a tripping mechanism comprising a cam gear 140 rotatably mounted on a stud 75 fixed to base plate 10. Cam gear 140 forms a rotatable support for cams 89, 100, 107, and 71, mentioned hereinbefore in connection with various lever which they operate. There is also provided on the gear a pin 128 for operating lever 60 and resetting lever 132. For driving cam gear 140, there is provided a pinion gear 142 which is fixed to the turntable shaft 12. One revolution of cam gear 140 defines the time interval required to carry out a record-changing cycle, and for terminating a record-changing cycle the gear is mutilated as at 143 by removing a suitable number of teeth.

For initiating the operation of cam gear 140, there is provided a pin or other suitable projection 144 in the hub of pinion 142. For cooperating with pin 144 there is provided a lever 145 pivoted at 146 to gear 140 for rotation by lever 132 which is associated with the tone arm control mechanism. One end of lever 145 is provided with a lug 147 for engaging with lever 132. The other end of lever 145 is provided with a lug 148 of resilient material for engaging with the pin 144. When lever 132 moves lever 145 into such a position that lug 148 is in the path of pin 144, this pin imparts motion to gear 140 through lever 145 whereby gears 140 and 142 mesh with one another. For returning lever 145

to its idle position, there is provided a disc 149 on stud 61 for engaging lug 148 as gear 140 rotates through a cycle.

For energizing motor 19 and initiating operation of the phonograph apparatus, there is provided a switch 130 having four positions, "off," "manual," "automatic" and "reject." When switch 130 is in any other position than the "off" position, motor 19 is energized through a pair of conductors which are not shown. Switch 130 includes a crank arm 151 for engaging lug 152 on a pivoted plate 153. Plate 153 is pivoted on pin 155 to which is fixed lever 124 previously mentioned as being operated by the lug 121 on plate 117. Attached to plate 153 is a rod 156 which extends across gear 140 and terminates in a hooked portion 158, which projects into an aperture 160 in lever 132. Aperture 160 is dimensioned to allow a certain degree of free movement with respect to rod 156. Switch 130, when moved to the "manual" position, moves rod 156 into engagement with the outer edge of aperture 160 to prevent lever 132 from acting, but when the switch is in the "automatic" position, it positions rod 156 within the aperture 160 so that lever 132 can move freely. However, when switch 130 is moved to the "reject" position, rod 156 engages the inner side of aperture 160 and lever 132 is moved into engagement with lever 145 to trip gear 140 and cause it to carry out a record-changing cycle.

The record changer structure described hereinbefore operates in the following manner. It will be assumed that a number of records are placed on the supports comprising spindle shoulder 24 and shelf 32 of bracket 30. It will also be assumed that a single record is placed on turntable 14. Switch 130 is rotated to its third or automatic position for energizing motor 19 to automatically and successively reproduce one record after another. Tone arm 16 is placed in position to engage stylus 21 in the initial playing groove of the record and the stylus follows the spiral playing groove until eventually it tracks the eccentric change-control groove which imparts an oscillating motion to the tone arm. Throughout the period that the stylus tracks the playing groove, lever 132 is rotated by clutch 134 in a counterclockwise direction into engagement with lever 145 to move its end 148 toward pinion 142. The pinion is continuously rotated with the turntable 14 and pin 144 continually strikes the end 148 of lever 145 to rotate it in a counterclockwise (Fig. 4) direction, thereby to continually return lever 132 to its initial position. When the tone arm oscillates in the change groove of the record, the counterclockwise rotation of lever 132 becomes fast enough to move lever 145 in a clockwise direction far enough for pin 144 directly to engage the end 148 whereby the motion of pin 144 rotates cam gear 140 into mesh with pinion 142.

Cam gear 140, driven by pinion 142, makes one complete revolution back to its original position where mutilated portion 143 is adjacent pinion 142. During the revolution of gear 140, lever 145 is reset to its idle position when disc 149 on stud 61 engages end 148 of lever 145. Lever 132 is reset as pin 128 on gear 140 engages ear 133 on the lever. This revolution of the cam gear carries out a complete change cycle to automatically place a new record on the turntable. When the cam gear starts its rotation from its idle position, the surface of cam 107 depresses the end 108 of lever 105 and thereby elevates pin 103 to lift tone

arm 16 and compress spring 104. After tone arm 16 is elevated, cam 100 rotates lever 95 in a counterclockwise direction whereby the pin 93 and lever 92 are rotated in a clockwise direction to rotate shaft 91 and tone arm 16 beyond the periphery of the record on the turntable.

Simultaneously with the movement of the tone arm, the surface 71A of cam 71 (Fig. 2) depresses and rotates lever 70 in a clockwise direction to 10 elevate spindle 22 and therewith the records supported on shoulder 24. The surface of cam 71 holds spindle 22 in its elevated position, and cam 89 rotates lever 85 in a counterclockwise direction to 15 rotate crank arms 82 which in turn rotate record supports 80 to a position underneath the records which have been elevated by spindle 22.

After the auxiliary supports 80 are rotated in this manner, cam 71 permits lever 70 to return to its normal position thereby lowering spindle 22 to in turn lower the records onto supports 80. When the spindle is free of the records, pin 128 on cam gear 140 is rotated sufficiently to engage the end 63 of lever 60 and rotate it in a counterclockwise direction (Fig. 7). Rotation of lever 25 60 causes it to engage with the lower end of lever 54 and rotate it in a counterclockwise direction (Fig. 8) to move the record-moving member 35 toward the spindle 22. The shelf 38 of member 35 moves under the lowermost record 30 in the stack of records, and the shoulder 37 engages the lowermost record and moves its centering aperture into alignment with spindle 22. However, the lowermost record cannot drop by reason of the fact that it is supported on shelf 38 and auxiliary supports 80.

When the centering aperture of the record has been moved into alignment with the spindle 22, surface 71B of cam 71 again depresses lever 70 and elevate spindle 22 through the aperture of 40 the lowermost record and into engagement with the superimposed record to lift the remaining records in the stack free of the lowermost record. Thus the entire stack of records is supported on shoulder 24 of spindle 22. Thereafter cam 89 returns lever 85 and auxiliary supports 80 to their respective initial positions and pin 128 on cam gear 140 moves out of contact with lever 60 whereby spring 62 returns lever 60 to its initial position and therewith record-moving member 35 45 to its initial position. The movements of auxiliary supports 80 and record-moving member 35 are timed so that these members simultaneously release the lowermost record to drop on the turntable. After the lowermost record is dropped to the turntable, cam 100 (Fig. 4) allows lever 95 to move in a clockwise direction under the influence of spring 109 whereby pin 93 and lever 92 are rotated in a counterclockwise direction to in turn move the tone arm back to a position over 50 the initial playing groove of the newly-dropped record.

At this time, cam 107 allows lever 105 to return to its initial position under the influence of spring 104 to lower pin 103 and tone arm 16 until stylus 65 21 engages the initial playing groove of the record. The tone arm tracks the spiral playing groove until it again engages the change groove in the record at which time the change cycle is repeated as described.

When the last record has been played by the pickup 17, the tone arm is oscillated as already described and a change cycle is initiated. The cam gear 140 rotates as described before, but the spindle is in its elevated position by reason of 70 the fact that there are no records on shoulder

24, and spring 76 rotates lever 70 in a clockwise direction (Fig. 2) to lift spindle 22. Soon after cam gear 140 commences its rotation, the rotatable plate 117 is rotated in a clockwise direction by reason of the fact that ear 121 engages the portion 77 of lever 70 to space the ear 118 away from the edge of cam 107. When lever 117 is in the position illustrated in Fig. 4, ear 118 engages the end of lever 112 and rotates it in a clockwise direction (Fig. 2) to elevate the hooked portion 113 above the plane of the extension 115 on lever 95, thus allowing lever 95 to place the tone arm in position to engage the initial playing groove of the record. However, when plate 117 has been rotated, as described above, to space the ear 118 away from cam 107, this ear cannot engage lever 112 whereby the hooked portion 113 remains in the plane of projection 115 on lever 95 to halt the movement of lever 95 so that tone arm 16 is not returned to a position over the initial playing groove of the record. Thus records may be removed from or placed on turntable 14 without striking tone arm 16.

Cam gear 140 continues its rotation and ear 121 engages the crank arm 124 connected to switch 130 to rotate the switch to its off-position whereby motor 17 is deenergized and the turntable ceases to rotate.

The record changer apparatus may be manually controlled by rotating switch 130 to the manual control position as indicated in Fig. 1. By so rotating the switch, the rod 156 is moved to such a position that its hooked portion 158 engages the outer edge of aperture 160 in lever 132 and prevents lever 132 from engaging lever 145. Thus even though the tone arm tracks the change groove in the record, lever 132 cannot initiate a record-changing cycle.

When switch 130 is rotated in a counterclockwise direction to the extreme position labeled "Rej." in Fig. 1, rod 156 is moved to such a position that its hooked portion 158 engages the inner edge of aperture 160 of lever 132 and moves it into engagement with lever 145 whereby cam gear 140 is moved into mesh with pinion 142 and a change cycle is initiated.

It is to be understood that this invention is not limited to the idea of elevating a stack of records by means of the spindle 22. For example, in Figs. 9, 10 and 11 there is shown a modification of this invention wherein the stack of records may be elevated by a pair of auxiliary supporting devices. There is provided a pair of pedestals 162 for supporting shafts 163, to the top of which is fixed rotatable record-supporting members 165. These members comprise two beveled shelf surfaces 165A and 165B, the first being adapted to support small records and the second being adapted to support large records. Both shelves are joined by a knife-edge 165C for moving under the peripheral edge of the lowermost supported record in the stack so that when members 165 are rotated, the beveled shelf members elevate the stack of records from the spindle.

The mechanism for rotating shelves 165 comprises pinion gears 169 and 170 fixed to the lower ends of shafts 163, rack member 171, lever 180 and cam 178 on cam gear 140. Rack member 171 is provided with apertures 172 which allow movement of the rack with respect to shafts 163, and for imparting movement to pinions 169 and 170 there is provided rack teeth 173 fixed to rack 171 whereby oscillating movement of member 171 imparts rotational movement to pinions 169 and 170 and shafts 163. Spring 175 is fixed between one

end of member 171 and base plate 10 for imparting movement in one direction to member 171 as will be explained hereinafter. Cam gear 140 is provided with cam groove 178 instead of a cam such as 89 illustrated in Figs. 3 and 4. Cam gear 140 otherwise consists of the same cam elements and is operated in the same manner as described hereinbefore in connection with the other modification of this invention.

The record-changing cycle is initiated in this modification in the same manner as in the previously described modification whereby the tone arm is initially moved beyond the periphery of the record on the turntable.

At the same time, portion 178A of cam 178 has no effect on lever 180. However, portion 178B of cam 178 rotates lever 180 in a counterclockwise direction to move rack 171 to the right. Such movement of rack 171 imparts motion to pinions 169 and 170 and shafts 163 as indicated by the arrows in Fig. 11. Shelves 165 move under the records to initially elevate the stack from shoulder 24 of spindle 22. Cam portion 178C of cam 178 maintains the records in elevated position during a time sufficient to permit the lowermost record to be moved into alignment with the spindle 22. The movement of the record is described hereinbefore in connection with the other modification of this invention. After the record has been moved, cam portion 178D and spring 175 moves lever 180 and rack 171 back to its normal position to lower the stack of records onto the shelf 24 of spindle 22. At this time the released record is dropped to the turntable and the tone arm is moved into engagement with the initial playing groove of the record.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What I claim is:

1. An automatic phonograph comprising a turntable, a spindle centered with respect to said turntable and including a shoulder adapted to engage the lowermost record of a record stack adjacent its centering aperture, a first peripheral record-supporting means including shelves movable for engaging the peripheral edge portions of either a small or a large record in said stack, a second peripheral record-supporting means disposed adjacent said turntable and opposite said first peripheral record-supporting means and pivotally mounted for movement under or away from the peripheral edge of said lowermost record, means for driving said phonograph, cam means operatively associated with said driving means and said spindle for elevating it, cam means operatively associated with said driving means and said second peripheral record-supporting means for rotating it into supporting relation with said lowermost record after said spindle is elevated, cam means operatively associated with said driving means and said spindle for lowering it after said second peripheral record-supporting means is operated, record-moving means operatively associated with said driving means and said movable shelves for moving them toward or away from said spindle to move a record to such a position that its centering aperture is in alignment with said spindle and to release a record and cam means opera-

tively associated with said driving means for returning said second peripheral record-supporting means to its original position simultaneously with movement of said shelves away from said spindle to drop said record to the turntable.

2. An automatic phonograph comprising a turntable, a pickup arm pivoted adjacent said turntable for movement in vertical and horizontal planes, a first record-supporting means adapted to engage the lowermost record of a record stack, a second record-supporting means including a shelf movable for engaging the peripheral edge portion of a record in said stack, a third record-supporting means disposed adjacent said turntable and opposite said second record-supporting means and mounted for movement into or out of engagement with said lowermost record, means for driving said phonograph, cam means operatively associated with said driving means and said first record-supporting means for elevating the stack, cam means associated with said driving means and said third peripheral record-supporting means for rotating it into supporting relation with said lowermost record after said first record-supporting means is elevated, cam means operatively associated with said driving means and said first record-supporting means for lowering it after said third peripheral record-supporting means is operated and record-moving means operatively associated with said driving means and said record-moving shelves for moving them toward or away from said spindle to move a record to such a position that its centering aperture is in alignment with said spindle and to release a record.

3. An automatic phonograph mechanism comprising a turntable, a spindle centered with respect to said turntable and including means for supporting a record stack adjacent the centering aperture of the lowermost record in the stack, stationary means adjacent the peripheral edge of the lowermost record in said stack for engaging and supporting said stack, means for elevating and lowering said spindle, peripheral supporting means movable into and out of position to intercept the lowermost record of said stack when it is elevated by said spindle, record-moving means operatively associated with said stationary record support for moving the lowermost record of said stack in a horizontal plane when said movable peripheral support is in engagement with said lowermost record and driving means operatively associated with said mechanism.

4. An automatic phonograph comprising a turntable, a spindle centered with respect to said turntable and including a notched portion for supporting a record stack adjacent the centering aperture of the lowermost record in the stack, stationary means adjacent the peripheral edge of the lowermost record in said stack for engaging and supporting said stack, auxiliary peripheral supporting means rotatable into a position to intercept the lowermost record of said stack, a record-moving support operatively associated with said stationary record support for moving the lowermost record of said stack in a horizontal plane into alignment with said spindle when said auxiliary peripheral support is in engagement with said lowermost record, cam means operable after said lowermost record is moved for elevating said spindle and therewith the record stack with respect to said lowermost record, and driving means operatively associated with said cam means and said supports for moving them to carry out a record changing cycle.

5. An automatic phonograph comprising a turntable, a spindle centered with respect to said turntable and including means for supporting a record stack adjacent the centering aperture of the lowermost record in the stack, means adjacent the peripheral edge of the lowermost record in said stack for engaging and supporting said stack, auxiliary peripheral supporting means movable into a position to intercept the lowermost record of said stack, record-moving means operatively associated with said stationary record support for moving the lowermost record of said stack in a horizontal plane into alignment with said spindle when said movable peripheral support is in engagement with said lowermost record, means operable after said lowermost record is moved for elevating said spindle and therewith the record stack with respect to said lowermost record and driving means operatively associated with said spindle elevating means and said supports for moving them to carry out a record changing cycle.

6. An automatic phonograph comprising a turntable, a first means for supporting a record stack adjacent the centering aperture of the lowermost record in the stack, peripheral supporting means movable into a position to intercept the lowermost record of said stack, record-moving means including a record support adjacent the periphery of said stack for separating the lowermost record from said stack when said movable peripheral support is in position to intercept said lowermost record, means operable after said lowermost record is separated for elevating said first means and therewith the record stack with respect to said lowermost record and driving means operatively associated with elevating means and said supports for moving them to carry out a record changing cycle.

7. In an automatic phonograph, a record separating mechanism comprising a spindle centered with respect to said turntable and including means for supporting a record stack adjacent the centering aperture of the lowermost record in the stack, means adjacent the peripheral edge of the lowermost record in said stack for supporting said stack, record-moving means operatively associated with said record supporting means for moving the lowermost record of said stack in a horizontal plane into alignment with said spindle, means operable after said lowermost record is moved for elevating said spindle and therewith the record stack with respect to said lowermost record and driving means operatively associated with said spindle and said record moving means for separating the lowermost record from said stack.

8. An automatic phonograph comprising a turntable, a spindle centered with respect to said turntable and including means for supporting a record stack adjacent the centering aperture of the lowermost record in the stack, means adjacent the peripheral edge of the lowermost record in said stack for cooperating with said spindle to support said stack, auxiliary peripheral supporting means movable into a position to intercept the lowermost record of said stack, record-moving means operatively associated with said stationary record support for moving the lowermost record of said stack in a horizontal plane into alignment with said spindle when said movable peripheral support is in engagement with said lowermost record, means operable after said lowermost record is moved for elevating said spindle and therewith the record

stack with respect to said lowermost record, cam means operable to withdraw said auxiliary supporting means and said record moving means from said lowermost record, and driving means operatively associated with said spindle, said cam means and said supports for moving them to carry out a record changing cycle.

9. An automatic phonograph comprising a turntable, a spindle centered with respect to said turntable and including means for supporting a plurality of records adjacent the centering aperture of the lowermost record, means adjacent the peripheral edge of the lowermost record for engaging and supporting said records, auxiliary supporting means movable into a position to engage the lowermost record, record-moving means adjacent the periphery of said lowermost record for moving it into alignment with said spindle when said auxiliary support is in engagement with said lowermost record, means operable after said lowermost record is moved for elevating said spindle and therewith all but the lowermost record and driving means operatively associated with said spindle, said auxiliary support, said record moving means and said spindle elevating means for moving them to carry out a record changing cycle.

10. An automatic phonograph comprising a turntable, a first linearly movable record supporting means spaced above said turntable and adjacent thereto, a second peripheral record supporting means in a plane substantially with that of said first record supporting means for engaging the peripheral edge portion of a record, a third peripheral record supporting means peripherally spaced from said second peripheral record supporting means in substantially the same plane with said first record supporting means and movable under or away from a record on said first record supporting means, means for driving said phonograph through a record changing cycle, means operatively associated with said driving means and said first record supporting means for successively and repeatedly elevating and lowering said first record supporting means, means operatively associated with said driving means and said third peripheral record supporting means for moving said third peripheral record supporting means under a record during a first elevation of said first record supporting means, and away from said record during a second elevation of said first record supporting means and means operatively associated with said driving means and said second peripheral record supporting means for moving said second peripheral record supporting means toward said first record supporting means when said first record supporting means is first lowered and away from said first record supporting means when said third peripheral record supporting means are moved away from said record.

11. An automatic phonograph comprising a turntable, a first linearly movable record supporting means spaced above said turntable and adjacent thereto, a second peripheral record supporting means in a plane substantially with that of said first record supporting means for engaging the peripheral edge portion of a record, a third peripheral record supporting means peripherally spaced from said second peripheral record supporting means in substantially the same plane with said first record supporting means and movable under or away from a record on said first record supporting means, means for driving said phonograph through a record chang-

ing cycle, cam means operatively associated with said driving means and said first record supporting means for successively and repeatedly elevating and lowering said first record supporting means, cam means operatively associated with said driving means and said third peripheral record supporting means under a record during a first elevation of said first record supporting means and away from said record during a second elevation of said first record supporting means and a cam operatively associated with said driving means and said second peripheral record supporting means for moving said second peripheral record supporting means toward said first record supporting means when said first record supporting means is first lowered and away from said first record supporting means when said third peripheral record supporting means are moved away from said record.

12. An automatic phonograph comprising a turntable, a linearly movable spindle extending above said turntable and centered with respect to said turntable and including a record support spaced from said turntable, a first peripheral record supporting means in a plane substantially with that of said support and movable for engaging the peripheral edge portion of a record, a second peripheral record supporting means peripherally spaced from said first peripheral record supporting means in substantially the same plane with said record support and movable under or away from a record on said record support, means for driving said phonograph through a record changing cycle, cam means operatively associated with said driving means and said spindle for successively and repeatedly elevating and lowering said spindle during a record changing cycle, cam means operatively associated with said driving means and said second peripheral record supporting means for moving said second peripheral record supporting means under a record during a first elevation of said spindle and away from said record during a second elevation of said spindle and a cam operatively associated with said driving means and said first peripheral record supporting means for moving said first peripheral record supporting means toward said spindle when said spindle is first lowered and away from said spindle when said second peripheral record supporting means are moved away from said record.

13. An automatic phonograph comprising a turntable, a linearly movable spindle extending above said turntable and centered with respect to said turntable and including a record supporting shoulder spaced from said turntable, a peripheral record supporting means in a plane substantially with that of said shoulder and including shelves movable for engaging the peripheral edge portions of either a small or a large record, an auxiliary peripheral record supporting means peripherally spaced from said peripheral record supporting means in substantially the same plane with said record supporting shoulder and movable under or away from a record on said record supporting shoulder, means for driving said phonograph through a record changing cycle, cam means operatively associated with said driving means and said spindle for successively and repeatedly elevating and lowering said spindle during a record changing cycle, cam means operatively associated with said driving means and said auxiliary record supporting means for moving said auxiliary record supporting means under a record during a first elevation of said

spindle and away from said record during a second elevation of said spindle and a cam operatively associated with said driving means and said shelves for moving said shelves toward said spindle after said spindle is first lowered and away from said spindle when said auxiliary record supporting means are moved away from said record.

14. An automatic phonograph comprising a turntable, a linearly movable spindle extending above said turntable and centered with respect to said turntable and including a record supporting shoulder spaced from said turntable, a peripheral record supporting means in a plane substantially with that of said shoulder and including shelves movable for engaging the peripheral edge portions of either a small or a large record, an auxiliary peripheral record supporting means comprising a pair of record supporting members peripherally spaced from said peripheral record supporting means in substantially the same plane with said record supporting shoulder and movable under or away from a record on said record supporting shoulder, means for driving said phonograph through a record changing cycle, cam means operatively associated with said driving means and said spindle for successively and repeatedly elevating and lowering said spindle during a record-changing cycle, cam means operatively associated with said driving means and said members for moving said members under a record during a first elevation of said spindle and away from said record during a second elevation of said spindle and a cam operatively associated with said driving means and said shelves for moving said shelves toward said spindle after said spindle is first lowered and away from said spindle when said members are moved away from said record.

15. An automatic phonograph comprising a turntable, a linearly movable spindle extending above said turntable and centered with respect to said turntable and including a record supporting shoulder spaced from said turntable, a peripheral record supporting means in a plane substantially with that of said shoulder and including shelves movable for engaging the peripheral edge portions of either a small or a large record, an auxiliary peripheral record supporting means comprising a pair of record supporting members peripherally spaced from said peripheral record supporting means in substantially

the same plane with said record-supporting shoulder and movable under or away from a record on said record-supporting shoulder, linkage means connecting said members, means for driving said phonograph through a record-changing cycle, cam means operatively associated with said driving means and said spindle for successively and repeatedly elevating and lowering said spindle during a record-changing cycle, cam and lever means operatively associated with said driving means and said linkage means for moving said members under a record during a first elevation of said spindle and away from said record during a second elevation of said spindle and a cam and lever operatively associated with said driving means and said shelves for moving said shelves toward said spindle after said spindle is first lowered and away from said spindle when said members are moved away from said record.

16. An automatic phonograph comprising a turntable, a spindle extending above said turntable and movable linearly with respect thereto and centered with respect to said turntable and including record-supporting means spaced from said turntable, movable record moving means in a plane substantially with that of said record-supporting means, at least one auxiliary peripheral record-supporting means peripherally spaced from said movable means in substantially the same plane with said record-supporting means and said movable means and movable into and out of position to intercept the lowermost record on said spindle when it is elevated and means operatively connected with said spindle, said movable means and said auxiliary record-supporting means for successively elevating said spindle, moving said auxiliary supporting means to its intercepting position, lowering said spindle, moving said movable means, elevating said spindle, and moving said auxiliary supporting means from its intercepting position.
